UNITED STATES PATENT OFFICE

WILLIAM C. KOCH, OF ST. PAUL, MINNESOTA

BUILDING CONSTRUCTION

Application filed June 27, 1927. Serial No. 201,618. .

This invention relates to an improved method of constructing dwellings and other buildings, particularly by the use of brick or other masonry as the outer shell of the walls 5 and a suitable concrete as a backing or sustaining body.

It is my object to provide a novel method of constructing walls whereby great strength and durability is imparted thereto, and a 10 wall having high heat insulating qualities is produced.

A further object is to reduce the cost of masonry and concrete buildings by eliminating the forms or false works usually required 15 where concrete is employed and also by minimizing the time required for the erection of the walls.

The invention will be best understood by reference to the accompanying drawing in 20 which Figure 1 is a horizontal section through a portion of a wall formed by my improved process; Fig. 2 is a fragmentary external elevation of the wall; Figs. 3 and 4 are fragmentary internal elevations with plaster 25 removed showing the spacing members in connection with different types of plaster supports or laths; and Figs. 5 and 6 are plan and side elevations respectively of suitable spacing members for use in constructing the 30 wall, Fig. 6 also showing suitable metal lath in vertical section.

As illustrated, my improved wall comprises an outer shell 7 of brick or other suitable masonry, spacing members 8, plaster 35 support 9, covered with plaster 10, and a concrete sustaining body 11. The spacing members 8, as shown in Figs. 5 and 6, are preferably constructed from suitable heavy gauge wire which is bent to form a loop 12 and then 40 extended in a plane perpendicular to the loop 12 to form abutments 14 for engagement with the inner surface of the wall 7. From these abutments 14, the member 8 extends perpendicularly a distance about equal to the thickness 45 of the concrete portion of the wall, and its normally inner end is formed with a fork 13 for engaging the plaster support 9, the wire being crossed at the point 15 to form a stop to engage the outer surface of the plaster support 9.

Any suitable plaster support or backing 55 may be used such as the perforated metal plate 16 shown in Fig. 3, or the expanded metal lath 17 shown in Fig. 4. The plate 16 has openings 19 through which the forks 13 may be inserted, and the lath 17 is of the common type formed with diamond shaped openings.

In the construction of a building, a suitable 60 foundation is formed, and then the brick wall 7 is erected in the usual manner upon the foundation. This wall is sufficiently self sustaining when made approximately four 65 inches in thickness. During the construction of this wall, spacing members 8 are inserted in placed relation, vertically and horizontally, as indicated in Figs. 1 and 2. After a row of bricks has been laid, the spacing members 8 are embedded in the mortar 70 between bricks with the loops 12 in a horizontal plane and the abutment members 14 engaging the inner surface of the brick as indicated. In this manner a self sustaining outer shell of the building is constructed and the spacing members 8 are firmly held therein when the mortar has set. During the erection 75 of the outer shell, the mill work, such as door and window frames, (one of which is indicated by the numeral 18 in Fig. 1) is mounted in the wall and allowed to project 80 from the inner surface thereof.

After a section of the wall or outer shell 7 has been constructed as described above, the next step in the operation is to secure the 85 plaster support 10 to the inner ends of the members 8, leaving a space between the outer shell and the plaster support. To accomplish this, it is only necessary to extend the forked end 13 of each spacing member through an opening 19 in the type of plaster support 90 shown in Fig. 3, and then to bend the ends laterally, or to secure one of the wires of the metal lath shown in Fig. 4 between the forked ends as indicated in dotted lines in Fig. 6. The crossed portion 15 of the wire furnishes 95 a stop or indicates the proper location of the plaster support relative to the wall 7. After inserting the forked ends 13 they are bent laterally to engage and hold the plaster support 10 firmly in proper spaced relation to 100

the outer shell 7. Upon the inner shell of the wall thus formed the rough plaster is now applied in the usual manner. When the plaster has set sufficiently to seal the 5 openings in the plaster support, the concrete 11 may be poured into the space between the brick wall 7 and inner shell formed by the plaster support and plaster. I prefer to employ a concrete of light weight and having 10 good insulating quality, such as that which contains a large proportion of argillaceous material burned at temperatures of from 1700 to 2200 degrees Fahrenheit in place of sand and crushed rock or gravel. Such concrete 15 of light weight may be poured in a section of the wall of a few feet in height so that excessive hydro-static pressure will not be applied to the inner shell. When one section of concrete has set, the other sections may be 20 poured successively until the wall is complete. Preferably the entire inner shell of the wall should not be constructed until after the lower portion of the concrete 11 has been poured. Where water pipes or other 25 conduits are to be embedded in the wall they are constructed before pouring the concrete. The time required to construct a building is reduced by my improved method because the masons laying the brick or other material 30 for the outer shell may be employed upon one portion of the wall while workmen constructing the inner shell and pouring concrete may be employed on other portions simultaneously. Further, a large part of the frame of the 35 building, such as studding, is eliminated as well as all false works for retaining the concrete. The spacing members 8 insure uniformity in the spacing of the outer and inner shells. Thus when the outer shell has been 40 properly constructed the location of the inner shell and thickness of concrete is accurately fixed by the spacing members.

Having described my invention what I claim is new and desire to protect by Letters 45 Patent is:

The method of constructing buildings, which consists in erecting a thin, outer, permanent but only temporarily self sustaining shell, consisting of a single thickness of face 50 brick and securing between said brick a multiplicity of spacing members arranged to project inward therefrom, then securing to said spacing members in spaced relation to said outer shell, an inner shell consisting of a 55 foraminous plaster support constituting a permanent portion of the wall, then applying plaster to said inner shell and allowing the same to harden with portions thereof 60 projecting into the space between said inner and outer shells and finally rendering the wall permanently self sustaining by filling the space between said outer and inner shells with a relatively thick plastic body of concrete or the like and allowing said body to 65

harden and form a direct, permanent bond between said plaster and the outer shell.

In testimony whereof, I have hereunto signed my name to this specification.
